DESIGN FOR A DRESS ENSEMBLE

Gertrude Bates, New York, N. Y.

Application October 30, 1940, Serial No. 96,185

Term of patent 3½ years

To all whom it may concern:

Be it known that I, Gertrude Bates, a citizen of the United States of America, residing in New York city, county of Kings, and State of New York, have invented a new, original, and ornamental Design for a Dress Ensemble, of which the following is a specification, reference being had to the accompanying drawing, forming part thereof, wherein,

The characteristic feature of my design resides in the combination on the ensemble disclosed of the specific embroidered jacket member in association with the specific dress member all as shown.

I claim:

The ornamental design for a dress ensemble, substantially as shown and described.

GERTRUDE BATES.
